UNITED STATES PATENT OFFICE.

STEPHEN M. BALZER, OF NEW YORK, N. Y., ASSIGNOR OF ONE-HALF TO
WILLIAM H. HUMPHREY, OF NORFOLK, CONNECTICUT.

TYPE-WRITING MACHINE.

SPECIFICATION forming part of Letters Patent No. 608,634, dated August 9, 1898.

Application filed April 5, 1893. Serial No. 469,224. (No model.)

To all whom it may concern:

Be it known that I, STEPHEN M. BALZER, a citizen of the United States, residing at New York, county of New York, and State of New York, have invented certain new and useful Improvements in Type-Writing Machines, fully described and represented in the following specification and the accompanying drawings, forming a part of the same.

10 This invention relates to type-writing machines, and especially to that class of machines in which the type are grouped upon one or more carriers as distinguished from machines in which each type is mounted independently, the most common form of machines of this class being that known as "wheel" machines, in which the type are placed upon a rotating carrier, such as a wheel or segment, and the latter rotated in one or both directions to position it for the impression of the desired character, the impression being made either by a hammer or by the movement of the type-carrier against the paper. The machines heretofore constructed on this principle have not been found satisfactory in operation, chiefly on account of the difficulty of securing accurate positioning of the type-carrier for the impression of the desired character and its certain retention in such position during printing, especially at a high rate of speed or after wear of the mechanism by use.

15 One of the special objects of the present invention is to provide an improved type-movement for such machines by which the type-carrier is under positive control and positively locked in position before and during the action of the impression mechanism, so that a correct impression is secured at any rate of speed at which the machine can be operated.

While the improved type-movement by which the type-wheel is positioned and held during printing is applicable generally to machines of the class referred to, whether the impression be produced by the movement of the type-carrier against the paper or by a hammer pressing the type against the paper or the paper against the type, it is of especial value as applied to machines in which the type-carrier is moved against the paper

for printing; and a further object of the invention is to provide an improved machine of this special class. Such machines are especially liable to inaccurately position the type-carrier and make imperfect impression, especially when operated at high rates of speed, because the type-carrier is liable to be moved bodily out of position before the type-carrier is properly positioned or to yield so as to permit the type-carrier to overthrow in the positioning operation even with the devices heretofore used for locking the type-carrier in position during the impression. This difficulty is avoided in accordance with the present invention by positively locking the type-carrier against bodily movement during the action of the positioning mechanism. An important improvement is secured also by locking the key, type-carrier, and positioning mechanism together during the impression movement, so that these parts all move together as a single construction after the type-carrier is positioned. When these features are combined with the improved type-movement by which the type-carrier is positioned, the carrier is first brought into and locked in position for the impression of the character corresponding to the key actuated, during which time the carrier is positively held against bodily movement, and then the type-carrier released to permit bodily movement and moved against the paper for printing, while the key, type-carrier, and positioning mechanism are all locked together during the bodily movement of the carrier and the type-carrier still locked in position for the impression of the proper character. There are preferably provided also means by which when any key is actuated all the other keys are locked against movement, and thus held until the type-carrier and type-movement have returned to normal position.

In connection with the construction of a machine embodying the main features of the invention there have been devised also certain specific features of construction and combinations of devices, which in themselves form parts of the present invention.

For a full understanding of the invention a detailed description of a machine embodying all the improvements in their preferred form

will now be given in connection with the accompanying drawings, forming a part of this specification, and the features forming the invention specifically pointed out in the claims.

- 5 In the drawings, Figure 1 is a plan view of the machine. Fig. 2 is a section on the line 2 of Fig. 1. Fig. 3 is a horizontal section, on an enlarged scale, taken below the top plate of the machine, the position of the platen and 10 feed-rack being indicated in dotted lines. Fig. 4 is a vertical section on the line 4 of Fig. 3, looking to the rear, with the paper-carriage. Figs. 5 and 6 are vertical longitudinal sections on the line 5 of Fig. 4, showing the parts 15 in different positions, the ribbon-movement being omitted. Figs. 7 and 8 are detail plan views of the type-movement, corresponding to Fig. 3, but showing the parts in different positions. Fig. 9 is a cross-section on the line 20 9 of Fig. 3, looking to the left. Fig. 10 is a central section through the wheel-frame. Fig. 11 is a detail plan of the ribbon-feed. Figs. 12 and 13 are respectively an end view and central cross-section of the carriage-spring construction. Fig. 14 is a detail hereinafter referred to.

The scale of Figs. 1 and 2 is half size and of the others full size of a machine embodying the invention in convenient form.

- 30 The frame of the machine is shown as formed of the base-plate A, the two side frames B C, supporting the carriage, and a top plate D, mounted on standards E on the base-plate A, this top plate D supporting the type-wheel and operating parts therefor and the ribbon-movement and covering the machine between the carriage and finger parts of the keys. It will be understood, however, that a frame of any other suitable construction may be used. 35 40 The type-carrier, as shown, consists of a wheel F, which is loose on a sleeve 10, extending through slot 11 in the top plate D, this sleeve 10 being carried by the wheel-frame, which, as shown, consists of a bar 12, pivotally mounted in a bearing 13, carried by the top plate D, the bar 12 being provided with a hollow hub 14, mounted in said bearing, so that the bar 12 is supported just below the under side of the top plate D. If but one row 45 50 of type were to be used on the wheel F, it might be mounted rigidly on a shaft carried by the bar 12 and projecting through the top plate D; but it is preferable to use a plurality of rows of type, so as to diminish the positioning movement of the type-wheel, and the type-wheel is shown mounted as usual in such constructions, a shaft 15, by which the type-wheel is actuated, passing through the sleeve 10, which forms a bearing therefor and being 55 60 provided at the top with a forked arm 16, engaging a pin 17, carried by the type-wheel, so that the type-wheel rotates with the shaft 15, while free to slide upon the sleeve 10, the type-wheel being provided with the usual collar 65 18, engaged by any suitable devices for shifting the type-wheel to change the row of characters.

The shaft 15 carries at its lower end, below the bar 12, a cross-piece 19, to one end of which is pivoted one arm 20 of a three-armed lever 70 a, this lever forming a positioning member, by the movement of which the type-wheel is rotated into position for the impression of the character desired and being provided with two other arms 21 22, extending at right angles to the arm 20. The lever a is carried by a rod c, to which it is pivotally connected at the junction of the three arms 20 21 22, this rod being supported by and sliding in brackets 23, depending from the top plate D, the 80 rod c being drawn toward the front of the machine and normally held in this forward position by a spring 24, secured to the pin 25 in the top plate D and to the end of the rod c. The arm 20 of the lever a is connected to 85 the cross-piece 19 by a stud or pin 1 on the cross-piece entering an opening in the arm 20, which is preferably made a little larger than the pin, as shown in Fig. 14, for the purpose presently to be described. The opposite 90 end of the cross-piece 19 carries a similar pin 2, entering a long slot in a link 26, which is carried by and pivotally connected at its opposite end to a rod b, similar to the rod c previously described and mounted in the same 95 manner in brackets 23, this link forming a stopping member by which the type-wheel is stopped and held in proper position when positioned by the movement of lever a.

It will be seen that in the normal position 100 of the parts, as shown in Fig. 3, the type-wheel and shaft are at dead-center to the lever a in the line of bodily movement and also at dead-center relatively to the link 26, as the pin 2 is diametrically opposite the pin 1. By 105 the rocking of the lever a, therefore, the type-wheel and its shaft 10 will be thrown off the dead-center, and then the wheel, if necessary, rotated further by the bodily movement of the lever, this being permitted by the slot in 110 the link 26, this link serving to stop and hold the type-wheel in position by the engagement of the pin 2 with the link at one end of the slot, and the link being actuated in accordance with the movement of the lever a and 115 the character to be printed.

The cross-arms 21 22 of the lever a carry at their outer ends pins 3 4, which are engaged, respectively, by plates 27 28, carried, respectively, by rods d e, mounted and sliding in the brackets 23 in the same manner as rods b c, previously described. These plates 27 28 are cut away on their inner forward edges so as to first engage, respectively, the pins 3 4 on the respective arms 21 22 as the 120 rods d e move rearward in the brackets 23, and then their reduced portions come in contact with the central pin 5 of the lever a, the plates 27 28 being arranged at different levels, as shown in Fig. 9, so as to permit them to 125 pass each other, so that either of them may engage the pin 5. It will be seen also from Figs. 5 and 6 that the pins 1 2, arm 20, and link 26 are so arranged that the arm and link 130

are at different levels, and the cross-piece 19 may thus be carried into any position, rotating in either direction from the normal position, the arm and link passing each other.

5 The keys G are pivoted upon a bar H, mounted in the side frames B C at the rear of the machine and are each provided with a depending arm 29, which arms move between guides formed of teeth in a plate 30, 10 the keys being returned to position by springs 31, connected to the keys and plate. Behind the arms 29 are mounted bails I I' K, these bails consisting in the preferred form shown of cross-bars 32 in the path of the arms 29 and 15 vertical side arms 33, by which the bails are pivoted on the bar H. The bails I I' each extend over one-half the width of the machine, so as to be engaged each by one-half of the keys, while the bail K extends the full 20 width of the machine and is actuated by all the keys. Near the center of the machine widthwise each of these bails I I' K is connected by links 34 to vertical levers i i' k, corresponding to the respective bails, these 25 levers being pivoted in brackets 36 on the base-plate A and forked at their upper ends so as to engage pins 6 on the sliding rods previously described, the levers i i' k being connected, respectively, to rods d e b.

30 It is necessary that the bails I I' and the keys G should be so constructed and arranged that the keys will move the bails I I' different distances, so as to position the type-wheel for the impression of the character corresponding to the key actuated. This result 35 may be attained by varying the construction of the different keys or the construction of different parts of the bails in accordance with the keys, or any other suitable means may be 40 used for securing this result in connection with the other features of the invention, but this result is preferably attained by the construction shown, by which a very simple, cheap, and efficient construction is provided.

45 In this construction all the keys are the same in construction, and the proper variation in the movement of the type-wheel is secured by adjusting-screws l, carried by the bails I I' and corresponding to the keys G, so 50 that by the adjustment of these screws the proper movement of the bails may be secured in accordance with the key actuated. In order to secure the proper movement of the bail K by the different keys, this bail also is 55 provided with adjusting-screws m, similar to screws l. These adjusting-screws l m may be held in position when adjusted by any suitable means, but there is shown a device for this purpose which in itself forms a part of 60 the invention. In this construction the arms 32 of the bails are cut away so as to form forks through which the screws l m pass, and between these forks is placed a thin metal plate 37, which rests upon the screws l m and is 65 pressed down upon said screws by pressure-screws 38, passing obliquely downward through the bars 32, so that by forcing in

these screws the pressure of the plate 37 upon the screws l m may be increased and the latter held firmly in position, while by loosening the screws 38 the pressure of the plate is released, permitting the screws l m to be adjusted as desired.

The mechanism thus far described secures the positioning of the type-wheel in accordance with the character to be printed, the locking of the type-wheel in said position, and the moving of the type-wheel and wheel-frame rearward for the impression. With this mechanism is preferably combined a locking device by which the wheel-frame is held positively in position during the positioning of the type-wheel, and in the construction shown this locking device serves also to lock the key, type-wheel, and frame and the positioning 85 mechanism together during the impression movement and to lock all the other keys against movement when any one of the keys is actuated for printing and prevents the operation of a key until the key previously struck and other parts have returned to position. In this construction a locking bar or frame L extends the full width of the bank of keys G and is mounted loosely on a rod 39 at the base of the machine, so as to swing vertically below the depending arms 29 of the keys G and the bails I I' K. The bar L is so formed as to allow it to move upward without engaging the bails, but is provided with a shoulder 7, which normally is just below and to the rearward of the rear edges of the arms 29. The bar L is connected by a link 40 centrally of the machine to a horizontal arm 41 of the bell-crank lever n, mounted loosely on the bar H, another arm 42 of the bell-crank lever extending vertically and being connected by a link 43 to an arm 44 on the rear of the wheel-frame 12. In the construction shown the arm 42 is connected to the link 43 by a pin-and-slot connection, so as to allow the arm 42 to move rearward without moving the wheel-frame for a purpose presently to be described; but it will be understood that this is not essential so far as the action of the locking device is concerned and any other suitable form of connection may be used.

The lower ends of the arms 29 on keys G are curved for a short distance from their rear edges on a radius struck from the center 120 of the bar H and then cut on a curve of shorter radius or inclined so as to form a curve or incline of smaller radius or angle, the curve 8, struck on the longer radius, forming a locking-surface coacting with the shoulder 7 as the 125 keys are actuated to lock the bar L against upward movement, and thus hold the wheel-frame positively against rearward movement during the positioning operation, and then the curve or incline 8' engaging the shoulder 130 and locking the key, carrier-frame, and the bails and coöperating parts together during the impression movement, the bar L being permitted to rise as the carrier-frame moves

rearward, as fully described hereinafter in connection with the operation of the machine.

With the construction thus far described 5 any suitable paper-carriage, platen, and feed therefor may be used. There is shown a simple construction which will be found convenient and efficient and certain specific features in which form parts of the invention.

10 The carriage M is supported on front and rear rollers 45 in the frame of the machine by bars 46 47, running thereon, the front bar 47 forming the rack-bar by which the carriage is fed. The carriage is held firmly in position 15 while readily removable from the frame by a clip 48, secured to the rear of the frame by a screw 49 and overlapping the bar 46. By simply removing the screw 49 and clip 48 the carriage may be taken out.

20 The carriage M carries the usual paper-feeding roll and pressure-plate 50 51 and the platen h, which in the form shown consists of a metal bar, over which the paper is fed by the roll and plate 50 51, the paper being 25 guided as it is moved upward by the rod 53. The carriage is advanced for letter-spacing by a coiled spring, as usual in such constructions, the carriage being connected by a cord or band 54 to a hollow pulley o, to the inside 30 of which is attached a spring p, coiled about the bearing of the pulley. A spring construction is provided by which the tension of this carriage-feeding spring may conveniently be regulated as desired, which in itself 35 forms a part of the invention and is clearly shown in Figs. 12 and 13. In this construction the hub 55 of the pulley o runs in a hollow hub 56, which extends through and is mounted to rotate in a plate 57, fixed on the 40 frame and carries outside the plate a ratchet-wheel q and a thumb-piece r. Upon the plate 57 is mounted a finger-lever s, carrying two pawls 58, one of which will engage the ratchet-wheel q in each position as the lever is. 45 rocked, these pawls being so positioned that on each rocking of the lever so as to release one pawl and throw in the other the ratchet-wheel will be allowed to turn one tooth. One end of the spring p is attached to the pulley 50 o and the other to the hub 56 on ratchet-wheel q, and the pulley is secured in the hub 56 by a screw 59, which forms a bearing for the pulley. By this construction the spring 55 may readily be wound up as desired by the thumb-piece r, and in case the spring is too tight the proper tension may readily be secured by releasing the ratchet-wheel q and spring p step by step by the lever s.

The construction shown for releasing the 60 paper-carriage step by step for letter-spacing consists of the common fast-and-loose pawl device 60, which is carried by a lever 61, pivoted on the frame of the carriage so as to rock vertically and connected by a link 62 to an arm 63, extending rearward from the bell-crank n, mounted on the bar H and previously described in connection with the locking

movement, so that as the bell-crank is rocked rearwardly by the impression movement of the wheel-frame the pawl device is actuated 70 so that a letter-space movement is secured as the wheel-frame returns to position, as well understood in connection with similar carriage-feeds. It will be understood that any other suitable rack-releasing device may be 75 used in connection with the carriage-spring construction.

For word-spacing a space-key N is used, which is shown as pivoted at the base of the machine and connected to the link 40, so that 80 by actuating this space-key the bell-crank lever n on shaft H is rocked rearwardly and a spacing movement secured, as in the printing operation, the pin-and-slot connection of the arm 42 to the link 43, previously described, providing for lost motion sufficient to permit this spacing movement without movement of the wheel-frame.

The shifting devices for moving the type-wheel vertically to change the case may be 90 of any suitable construction. As shown, the collar 18 on the type-wheel is engaged by the forked end of an arm 64, carried by a pin 65, moving vertically in a central opening in the hub 14 on the frame 12, and this pin is raised 95 and lowered by a bar 66, carried by one end of a lever 67, pivoted in brackets on the under side of the top plate D and actuated by two keys S S' at one side of the machine, two shifts being used for three rows of characters, 100 as usual in such constructions.

Any suitable inking device may be used, either pad or ribbon, but a ribbon is preferred, and there is shown a ribbon-feed which will be found simple and efficient and forms a 10 part of the invention. In this construction the type-wheel is partially surrounded by a ribbon-guide 68, as usual, and the ribbon-spools R R' are placed on the top plate D in front of this guide, these ribbon-spools R R' being 11 mounted in any suitable manner so as to rotate in either direction and being provided with ratchet-wheels 69 by which they are driven. The wheel-frame carries a bar 70, extending 12 forward and sliding on the top plate D, this bar 70 being guided as the wheel-frame moves backward and forward by a pin 9, passing through a slot in the bar. At its front end this bar 70 carries a pawl-carrier 71, pivoted to swing transversely to the bar and having 13 at opposite sides pawls t, one of which engages one of the ratchet-wheels 69 as the bar 70 moves with the wheel-frame, according to the position of the pawl-carrier 71, which is held in position according to the ratchet-wheel to be actuated by notches cut in the pawl-carrier, and a small spring 72, entering either of said notches according to the position of the pawl-carrier and the spool to be actuated thereby. The ribbon is thus fed 14 from one spool to the other by one of the pawls t, and when the ribbon has been thus wound entirely onto one spool the pawl-carrier 71 is shifted so as to throw the other pawl

into engagement with the ratchet-wheel 69 on the other ribbon-spool and reverse the ribbon, as well understood in such constructions.

The operation of the construction will be understood from a brief description.

In the normal position of the parts, as shown in Figs. 3 and 5, with no key depressed, the type-wheel and wheel-frame are in their forward position away from the platen 52. The 10 sliding rods *b c d e* are all in their forward positions, and the bell-crank lever *a* is in its forward position, with the type-wheel at dead-center relatively to the arm 20, all these parts being held in position by the spring 24. The 15 locking-bar *L* is in its lowest position with the shoulder 7 just below and in front of the rear edges of the arms 29, and the bails *I I' K* are all in their forward positions. Assuming that the key actuated operates the bail *I* and rotates the type-wheel to the left through a large 20 part of its semicircumference, as shown in the drawings, the first action of the key upon the adjusting-screw *l* throws the bail *I* rearward and through connecting-rod 34 and lever *i* moves the rod *d* rearward in the brackets 25 23, so that the rear edge of the outer portion of the plate 27 engages the pin 3 on arm 21 and rocks the bell-crank lever *a*, so as to throw the type-wheel off the dead-center and into the position shown in Fig. 7, 30 the pin-and-slot connection 1 of the arm 20 to the cross-piece 19 permitting this movement and preferably being so formed as to allow no lost motion, but secure the continuous 35 movement of the wheel with the lever *a*. As the type-wheel is thus rotated, the pin 2 in the cross-piece 19 moves forward in the slot in the link 26, the rod *b* being stationary. The rod *d* has now been advanced so that the 40 inner cut-away portion of the plate 27 engages the pin 5 at the center of the bell-crank, by which it is connected to the rod *c*, and as the movement of the key, bail, and rod *d* continues the bell-crank *a* is moved forward 45 bodily to continue the rotation of the type-wheel to the left, the bell-crank carrying with it the rod *c* against the tension of the spring 24 and the pin 2 continuing to travel back in the slot in the link 26. At the proper time 50 the bail *K* is engaged by the arm 29 on the key being actuated through one of the adjusting-screws *m*, and this bail is then moved backward and through the link 34 and lever *k* moves the rod *b* rearward with the link 26 55 until the forward end of the slot in the link engages the pin 2, when the type-wheel is positioned for the impression of the letter corresponding to the key actuated and locked in this position by the pins 1 2, arm 20, and link 60 26 engaging the cross-piece 19 on opposite sides of the axis of the type-wheel and opposing each other.

In the construction shown, in which the type-wheel is moved against the paper for printing, the movement of the bails *I K* and rods *d b* is continued after the type-wheel is thus positioned and locked, so as to carry the

type-wheel frame rearward for the impression of the type against the paper on platen *h*, the rearward movement of both the lever *a* and link 26 maintaining the positive locking of the type-wheel against rotation during this movement and assuring a correct impression. 70

With the wheel-frame mounted on a vertical pivot, so as to swing in a horizontal plane, 75 as in the construction shown, it will be seen that the change of position of the type-wheel due to the arc through which the frame and type-wheel swing for the impression movement is compensated for automatically by the 80 lever *a* and link 26, so as to secure the impression of the face of the type squarely against the paper.

During the operation of positioning the type-wheel as thus far described the locking 85 device for the wheel-frame has operated to hold the wheel-frame positively in position, so that the movements described, although tending to move the type-wheel and wheel-frame, have produced no rearward movement 90 of the type-wheel, but only the rotary movement requisite for positioning it for the impression of the proper character. This result has been attained as follows: As the key *G* is depressed and the arm 29 thrown rearward the rear portion 8 first passes over the shoulder 7 and prevents the raising of the locking-bar *L* until this portion 8 has passed inside the shoulder and the front portion 8' is in engagement with the shoulder, when the 95 bar is permitted to rise during the further movement of the key, the bar still engaging this surface 8', however, so as to permit it to rise only in accordance with the movement of the key, and thus locking the key, wheel-frame, bar, and the bails and other parts of the positioning mechanism together. In the 100 position of the type-wheel and actuating parts shown in Fig. 7 the projection 29 on the key *G*, which is being actuated, is in the position shown in dotted lines in Fig. 5, and the surface 8 is just about to release the bar *L*, so as to allow the latter to rise for the rearward impression movement of the type-wheel. As the movement of the key *G* and bails *I K* 105 continues the rods *d b* carry the type-wheel and type-frame rearward, the key, wheel-frame, and positioning mechanism being locked together by the bar *L* and the type-wheel being positively locked in position for the impression of the character corresponding to the key actuated, as previously described, and as the type-wheel moves rearward the bell-crank *n* is rocked rearward 110 through the link 43 and by the connecting-rod 40 raises the locking-bar *L*, which has been released, as previously described, so that at the time of impression all the parts are brought into the position shown in Fig. 6. In 115 this position it will be seen that the locking-bar *L* has been raised, so as to bring the shoulder 7 in the path of the rearward movement of the arms 29 on the keys, so that all the keys are positively locked against movement, and 120 125 130

- this locking of the keys continues until the bar L is again lowered. When the impression is made, the key G, previously actuated, is released and all the parts returned to their 5 normal position, the key G being returned by the spring 31 and the type-wheel and wheel-frame being returned through bell-crank a, rod b, and spring 24, and the return of the type-wheel and wheel-frame returning the 10 bar L to its lowest position through the connections previously described. The forward movement of the rods d b, with the wheel-frame and bell-crank a, also returns the bails I K through the levers i k and connecting-rods 15 34. The feeding movement takes place during the return of the wheel-frame, as previously described, the movement of the wheel-frame in opposite directions actuating the pawls through the arms 63, link 62, and lever 20 61. The pawl t has been carried back one tooth on the ratchet 69 on one of the ribbon-spools, and on the return of the wheel from the ribbon-spool it rotates the ratchet-wheel one tooth and the ribbon is shifted. The parts 25 are now in position for printing another character, and thus the operation is repeated.
- In the operation described the bail I has been described as actuated before the bail K and the pin 2 as moving in the slot in link 26 30 before the link is moved; but this is only because the operation selected for illustration is that of positioning the type-wheel for the impression of a character requiring the rotation of the type-wheel through nearly a half-circumference or nearly the largest movement 35 of the type-wheel. It will readily be understood, therefore, by those skilled in the art that the bail K will in some cases be actuated before the bail I or I', so that the link 26 will 40 move forward before the type-wheel is rotated and the wheel then be rotated by the movement of bail I or I' while the movement of the link 26 continues, the result being the same as previously described. The time and 45 amount of movement of the bails I or I' and K depend, therefore, upon the position of the character on the type-wheel corresponding to the key actuated, and the movement of the bails is varied in accordance with the character 50 to be printed and their accurate movement secured solely by the adjustment of the screws l m, the keys G in construction and movement being all the same.
- It will readily be understood by those skilled 55 in the art that the means for positioning the type-wheel are of general application in type-writing machines of the different classes employing a type-wheel and may be used in machines of other general construction than that 60 shown.
- It will be understood that the invention is not to be limited to the exact construction or arrangement of the devices shown, but that many modifications may be made therein by 65 those skilled in the art without departing from the invention. It will be understood also that many of the features of invention

may be used in constructions not employing the other features and that the claims are intended to cover such use.

What I claim is—

1. The combination with a type-carrier, of a plurality of series of keys, a positioning member having a pivotal connection with the type-carrier, connections between said positioning member and keys for moving said type-carrier in different directions by the different series of keys to position the type-carrier, and stopping mechanism controlled by all the series of keys whereby the type-carrier is stopped and held in position, substantially as described. 70
2. The combination with a type-carrier and movable carrier-frame, of a plurality of series of keys, a positioning member having a pivotal connection with the type-carrier, connections between said positioning member and keys for moving said type-carrier in different directions by the different series of keys to position the type-carrier, and stopping mechanism controlled by all the series of keys 75 80 whereby the type-carrier is stopped and held in position, said positioning member and stopping mechanism having a further movement after the type-carrier is positioned whereby the frame is moved to carry the type-carrier against the paper for the impression, substantially as described. 85
3. The combination with a type-carrier, of a plurality of series of keys, a positioning member having a pivotal connection with the type-carrier, connections between said positioning member and the keys for moving said type-carrier in different directions by the different series of keys to position the type-carrier, a stopping member having a pivotal connection with said type-carrier and connections between said stopping member and the keys whereby the stopping member is controlled by all the series of keys to stop the type-carrier and hold it in position, substantially as described. 90 95 100
4. The combination with a type-carrier, of a plurality of series of keys, a positioning member having a pivotal connection with the type-carrier, connections between said positioning member and the keys for moving said type-carrier in different directions by the different series of keys to position the type-carrier, a stopping member having a pivotal connection with said type-carrier, and connections between said stopping member and the keys whereby the stopping member is controlled by all the series of keys to stop the type-carrier and hold it in position, substantially as described. 105 110 115
5. The combination with a type-carrier, of a plurality of series of keys, a positioning member having a pivotal connection with the type-carrier, connections between said positioning member and the keys for moving said type-carrier in different directions by the different series of keys to position the type-carrier, a stopping member having a pivotal connection with said type-carrier, and connections between said stopping member and the keys whereby the stopping member is controlled by all the series of keys to stop the type-carrier and hold it in position, said positioning and stopping members having a further movement after the type-carrier is positioned whereby the frame is moved to carry the type-carrier against the paper for the impression, substantially as described. 120 125 130

ating the positioning member to move the type-carrier in different directions by the different series of keys to position the type-carrier and a stopping member including a bail actuated by all the series of keys, whereby the type-carrier is stopped when positioned by one of the other bails, substantially as described.

70

5 6. The combination with a type-carrier, of

10 a plurality of series of keys, a positioning member having a pivotal connection with the type-carrier, bails and connections for actuating the positioning member to move the

15 type-carrier in different directions by the different series of keys to position the type-carrier, a stopping member, and a bail and connections actuated by all the series of keys whereby the stopping member is controlled to stop the type-carrier when positioned by

20 any one of the other bails, substantially as described.

80

6 7. The combination with a type-carrier, of

15 a plurality of series of keys, a positioning member having a pivotal connection with the type-carrier, bails and connections for actuating the positioning member to move the

20 type-carrier in different directions by the different series of keys to position the type-carrier, a stopping member having a pivotal con-

25 nection with said type-carrier, and a bail and

30 connections actuated by all the series of keys whereby the stopping member is controlled to stop the type-carrier when positioned by

35 any one of the other bails, said bails and

40 members having a further movement after

45 the type-carrier is positioned and stopped

50 whereby the frame is moved to carry the type-

55 carrier against the paper for the impression

60 substantially as described.

90

7 8. The combination with a type-carrier, of

10 a positioning member and a stopping mem-

15 ber having a pivotal connection with the type-

18 carrier, keys and connections for actuating

20 said positioning member to position the type-

25 carrier, and connections between the keys and

30 stopping member, whereby the latter is con-

35 trolled to stop and hold the type-carrier in

40 position, substantially as described.

100

8 9. The combination with a type-carrier, of

15 a positioning member and a stopping mem-

20 ber having a pivotal connection with the type-

25 carrier, keys and connections for actuating

30 said positioning member to position the type-

35 carrier, and connections between the keys and

40 stopping member, whereby the latter is con-

45 trolled to stop and hold the type-carrier in

50 position, substantially as described.

105

9 10. The combination with a type-carrier, of

15 a positioning member and a stopping mem-

20 ber having a pivotal connection with the type-

25 carrier, keys and connections for actuating

30 said positioning member to position the type-

35 carrier, and connections between the keys and

40 stopping member, whereby the latter is con-

45 trolled to stop and hold the type-carrier in

50 position, substantially as described.

110

10 11. The combination with a type-carrier, of

15 a positioning member and a stopping mem-

20 ber having a pivotal connection with the type-

25 carrier, keys and connections for actuating

30 said positioning member to position the type-

35 carrier, and connections between the keys and

40 stopping member, whereby the latter is con-

45 trolled to stop and hold the type-carrier in

50 position, substantially as described.

115

11 12. The combination with a type-carrier, of

15 a positioning member and a stopping mem-

20 ber having a pivotal connection with the type-

25 carrier, keys and connections for actuating

30 said positioning member to position the type-

35 carrier, and connections between the keys and

40 stopping member, whereby the latter is con-

45 trolled to stop and hold the type-carrier in

50 position, substantially as described.

120

12 13. The combination with a type-carrier, of

15 a positioning member and a stopping mem-

20 ber having a pivotal connection with the type-

25 carrier, keys and connections for actuating

30 said positioning member to position the type-

35 carrier, and connections between the keys and

40 stopping member, whereby the latter is con-

45 trolled to stop and hold the type-carrier in

50 position, substantially as described.

125

13 14. The combination with a type-carrier, of

15 a positioning member and a stopping mem-

20 ber having a pivotal connection with the type-

25 carrier, keys and connections for actuating

30 said positioning member to position the type-

35 carrier, and connections between the keys and

40 stopping member, whereby the latter is con-

45 trolled to stop and hold the type-carrier in

50 position, substantially as described.

130

keys and connections for rocking said lever in either direction to throw the type-carrier off the dead-center and movesaid lever bodily to rotate the type-carrier further, substantially as described.

17. The combination with a rotary type-carrier, of a rocking and bodily-moving lever connected to said type-carrier on one side of the axis, a member connected to the type-carrier on the opposite side of the axis, said type-carrier being normally at dead-center with the line of bodily movement of said lever and member, and keys and connections for rocking said lever in either direction to throw the type-carrier off the dead-center, and moving said lever and member to position and lock the type-carrier, substantially as described.

18. The combination with a rotary type-carrier, of a rocking lever pivotally connected to said type-carrier on one side of the axis, a link having a slotted connection to said type-carrier on the opposite side of the axis, and keys and connections for rocking said lever in either direction and moving said lever and link endwise, to position and lock the type-carrier, substantially as described.

19. The combination with a rotary type-carrier, of a rocking lever pivotally connected to said type-carrier on one side of the axis, arms on opposite sides of said lever, a link having a slotted connection to said type-carrier on the opposite side of the axis, sliding bars carrying said lever and link, sliding bars carrying members adapted to engage the opposite arms of said lever, series of keys and connections for actuating said bars to rock the lever and rotate the type-carrier in opposite directions, and connections between both series of keys and the sliding bar carrying the link, whereby the type-carrier is locked in position, substantially as described.

20. The combination with a rotary type-carrier and movable carrier-frame, of a rocking lever pivotally connected to said type-carrier on one side of the axis, a link having a slotted connection to said type-carrier on the opposite side of the axis, and keys and connections for rocking said lever in either direction and moving said lever and link endwise, to position and lock the type-carrier and move the carrier-frame for the impression, substantially as described.

21. The combination with a rotary type-carrier and movable carrier-frame, of a rocking lever pivotally connected to said type-carrier on one side of the axis, arms on opposite sides of said lever, a link having a slotted connection to said type-carrier on the opposite side of the axis from said lever, sliding bars carrying said lever and link, sliding bars carrying members adapted to engage the opposite arms of said lever, series of keys and connections for actuating said bars to rock the lever and rotate the type-carrier in opposite directions, and connections between both series of keys and the sliding bar carrying the link, whereby the type-carrier is first locked in po-

sition and then the carrier-frame moved for the impression, substantially as described.

22. The combination with the type-carrier and keys of a type-writing machine, of mechanism including a positioning member having a pivotal connection with said type-carrier for positioning the type-carrier by the movement of the keys and moving the type-carrier against the paper for the impression, and locking mechanism positively holding the type-carrier frame against movement during the carrier-positioning operation and released for the impression movement, substantially as described.

23. The combination with the type-carrier and keys of a type-writing machine, of mechanism for positioning the type-carrier by the movement of the keys and moving the type-carrier against the paper for the impression, and a locking-bar connected to the carrier-frame and extending transversely to the keys, and means for holding said locking-bar in position to lock the frame against movement during the carrier-positioning operation, substantially as described.

24. The combination with a type-carrier, of lever-keys, mechanism for positioning the type-carrier by the movement of the keys and moving the type-carrier against the paper for the impression, and a locking-bar connected to the carrier-frame and engaged and held in position by the keys to lock the frame against movement during the carrier-positioning movement of the keys and released for the impression movement, substantially as described.

25. The combination with a type-carrier, of lever-keys having arms extending at an angle to the keys, mechanism for positioning the type-carrier by the movement of the keys and moving the type-carrier against the paper for the impression, and a locking-bar connected to the carrier-frame and engaged and held in position by the arms during the carrier-positioning movement of the keys to hold the frame against movement and released for the impression movement, substantially as described.

26. The combination with a type-carrier, of lever-keys provided with surfaces curved substantially concentrically with the path of movement of said keys, mechanism for positioning the type-carrier by the movement of the keys and moving the type-carrier against the paper for the impression, and a locking-bar connected to the carrier-frame and engaged and held in position by the curved surfaces on the keys during the carrier-positioning movement and released by the curved surfaces for the impression movement, substantially as described.

27. The combination with the keys, type-carrier and movable carrier-frame, of mechanism for positioning the type-carrier by the movement of a key and moving the carrier-frame for the impression, and locking mechanism brought into action by the movement

of the key and locking the key, carrier-frame and positioning mechanism together during the impression movement of the frame, substantially as described.

5 28. The combination with the keys, type-carrier and movable carrier-frame, of mechanism for positioning the type-carrier by the movement of a key and moving the carrier-frame for the impression, and locking mechanism actuated by the impression movement of the frame and locking the key, carrier-frame and positioning mechanism together, substantially as described.

15 29. The combination with the keys, type-carrier and movable carrier-frame, of mechanism for positioning the type-carrier by the movement of a key and moving the carrier-frame for the impression, a locking-bar normally just outside the path of the key, and 20 connections between said locking-bar and carrier-frame whereby the bar is brought into and held in engagement with the key by the movement of the frame and the key, carrier-frame and positioning mechanism are locked 25 together during the impression movement, substantially as described.

30 30. The combination with a type-carrier and movable carrier-frame, of lever-keys provided with surfaces curved substantially concentrically with the path of movement of said 35 keys, and with surfaces curved or inclined on a different radius or angle, mechanism for positioning the type-carrier by the movement of the keys and moving the type-carrier frame for the impression, a locking-bar engaged and held in position by the concentrically-curved surfaces during the positioning movement, and connections between said bar and carrier-frame, whereby the carrier-frame is locked in 40 position by the bar during its engagement by the concentrically-curved surfaces of the keys and the bar held pressed against the other curved or inclined surfaces of the keys during the impression movement of the carrier, 45 substantially as described.

31. The combination with a type-carrier, of lever-keys, mechanism for positioning the type-carrier by the movement of the keys and moving the type-carrier against the paper for 50 the impression, a locking-bar engaged and held in position by the keys during the carrier-positioning movement of the keys and released for the impression movement, and connections between the locking-bar and carrier-frame whereby the bar is moved by the frame during the impression movement, said bar being mounted in position to be brought by said movement into the path of the keys, whereby the keys not actuated are locked in 55 their normal position, substantially as described.

60 32. The combination with the type-carrier and keys of a type-writing machine, of mechanism for positioning the type-carrier by the movement of the keys and moving the type-carrier against the paper for the impression, and locking mechanism positively holding the

type-carrier frame against movement during the positioning operation and released for the impression movement and locking the other 70 keys on the movement of one key until the return of the parts to their normal position, substantially as described.

75 33. The combination with the type-carrier and keys of a type-writing machine, of mechanism for positioning the type-carrier by the movement of the keys and moving the type-carrier against the paper for the impression, and mechanism actuated by the impression movement of the type-carrier locking the keys 80 in their normal position during the impression movement of the carrier, substantially as described.

85 34. The combination with rotary type-carrier F, of keys G, bails I, I' and connections including a member having a pivotal connection with said carrier for rotating said carrier in opposite directions to position the carrier, and bail K and connections for stopping and locking said carrier in position, 90 substantially as described.

95 35. The combination with rotary type-carrier F, and a movable carrier-frame, of keys G, bails I, I' and connections including a member having a pivotal connection with said carrier for rotating said carrier in opposite directions to position the carrier, and bail K and connections for stopping and locking said carrier in position, 100 said bails having a further movement after the type-carrier is positioned to move the carrier-frame for the impression, substantially as described.

105 36. The combination with rotary type-carrier F, and a movable carrier-frame, of keys G having arms 19 provided with curved surfaces 8, bails I, I' and connections for rotating said carrier in opposite directions to position the carrier, bail K and connections for stopping and locking said carrier in position, said bails having a further movement after 110 the type-carrier is positioned to move the carrier-frame for the impression, and locking-bar L connected to the carrier-frame locked by engagement of the keys, substantially as described.

115 37. The combination with rotary type-carrier F, and a movable carrier-frame, of keys G having arms 19 provided with curved surfaces 8 and curved or inclined surfaces 8', bails I, I' and connections for rotating said carrier in opposite directions to position the carrier, bail K and connections for stopping and locking said carrier in position, said bails having a further movement after the type-carrier is positioned to move the carrier-frame 120 for the impression, and locking-bar L connected to the carrier-frame and engaged by the curved surfaces, substantially as described.

125 38. The combination with rotary type-carrier F, and a movable carrier-frame, of keys G having arms 19 provided with curved surfaces 8 and curved or inclined surfaces 8', bails I, I' and connections for rotating said

carrier in opposite directions to position the carrier, bail K and connections for stopping and locking said carrier in position, said bails having a further movement after the type-carrier is positioned to move the carrier-frame for the impression, and locking-bar L connected to the carrier-frame and engaged by the curved surfaces, said bar and arms 19 being so constructed and located relatively to each other that the bar is brought by the impression movement into the path of the keys not actuated and the keys locked in normal position, substantially as described.

39. The combination with rotary type-carrier F, and a movable carrier-frame, of keys G having arms 19 provided with curved surfaces 8 and curved or inclined surfaces 8', bails I, I' and connections for rotating said carrier in opposite directions to position the carrier, bail K and connections for stopping and locking said carrier in position, said bails having a further movement after the type-carrier is positioned to move the carrier-frame for the impression, locking-bar L, link 40 and lever n having arms connected to the link and carrier-frame, substantially as described.

40. The combination with rotary type-carrier F, of lever a having arm 20 connected to said carrier on one side of the axis of the carrier, and arms 21, 22 on opposite sides of the pivot of said lever, and keys and connections for rocking said lever by either of its arms 21, 22 and then moving it bodily, substantially as described.

41. The combination with rotary type-carrier F, of lever a having arm 20 connected to the carrier on one side of its axis, and arms 21, 22 on opposite sides of the pivot of said lever, link 26 connected to the type-carrier by a slotted pivotal connection on the opposite side of the axis from the arm 20, said lever and link lying in different planes so as to pass each other, and keys and connections for rocking said lever a by either of its arms 21, 22, and moving the lever and link longitudinally, substantially as described.

42. The combination with rotary type-carrier F and movable carrier-frame, of lever a having arm 20 connected to the carrier on one side of its axis, and arms 21, 22, on opposite sides of the pivot of said lever, link 26 connected to the type-carrier by a slotted pivotal connection on the opposite side of the axis from the arm 20, said lever and link lying in different planes so as to pass each other, and keys and connections for rocking said lever a by either of its arms 21, 22, and moving the lever and link longitudinally, substantially as described.

43. The combination with rotary type-carrier F, of lever a having arm 20 connected to the carrier on one side of its axis, and arms 21, 22, on opposite sides of the pivot of said lever, link 26 connected to the type-carrier by a slotted pivotal connection on the opposite side of the axis from the arm 20, said le-

ver and link lying in different planes so as to pass each other, sliding rods c, b on which said lever and link are pivotally mounted, a spring for holding the rod c in its normal position, sliding rods d, e carrying members lying in different planes so as to pass each other, and engaging respectively first one of arms 21, 22 and on their further movement engaging also lever a in line with the axis, 75 and keys and connections for moving said rods to rock the lever a by either of its arms 21, 22, and move the lever and link longitudinally, substantially as described.

44. The combination with rotary type-carrier F, having cross-piece 19 on its shaft, of lever a having arm 20 pivoted loosely to the cross-piece on one side of the axis, and arms 21, 22 on opposite sides of the pivot of said lever provided with pins 3, 4, said lever and link 80 lying in different planes so as to pass each other, sliding spring-pressed rod c on which the lever is pivoted by pin 5, sliding rod b on which the link is pivotally mounted, and sliding rods d, e carrying plates 27, 28, lying 85 in different planes and each cut away opposite the center of lever a so as to first engage one of the pins 3, 4, substantially as described.

45. The combination with the carriage-spring and step feeding devices of a type-writer, and a ratchet for holding said spring under tension, of a double-pawl holding device for the ratchet forming a step-by-step releasing device therefor, substantially as described.

46. The combination with the carriage-spring and step feeding devices of a type-writer, of a pulley connected to the carriage, and within which the spring is coiled, a ratchet-wheel having a hub within said pulley, said carriage-spring being connected to the pulley and hub, and a finger-piece carrying a double-pawl holding device for the ratchet forming a step-by-step releasing device therefor, substantially as described.

47. The combination with the pulley o, of the spring p, ratchet-wheel q having finger-piece r and hub 56 to which the spring is connected, and finger-lever s having pawls 58, substantially as described.

48. The combination with the type-carrier and reciprocating carrier-frame of a type-writer, of a member connected to and moving with said type-carrier frame, ribbon-spools having ratchets, and a pawl-carrier carried 120 by said member and adjustable into position to engage either of said ratchets, substantially as described.

49. The combination with a type-carrier and reciprocating carrier-frame, of ribbon-spools mounted in front of said carrier and provided with ratchets, plate 70, pawl-carrier 71 on said carrier having pawls t, and movable on said plate into position to actuate either of said spools, substantially as described.

50. The combination with ribbon-spools R,

R' and ratchets 69, of sliding plate 70, pawl-carrier 71 pivoted on said plate, and carrying pawls *t*, and holding-spring 72, substantially as described.

5 51. The combination with the adjustable screws *l*, of pressure-plate 37, and pressure-screws 38, substantially as described.

In testimony whereof I have hereunto set my hand in the presence of two subscribing witnesses.

STEPHEN M. BALZER.
